UNITED STATES PATENT OFFICE.

BERRIEN H. SMITH, OF BROOKLYN, NEW YORK.

CANDY MOLD AND PRESS.

1,330,286.

Specification of Letters Patent. Patented Feb. 10, 1920.

Application filed September 13, 1919. Serial No. 323,527.

To all whom it may concern:

Be it known that I, BERRIEN H. SMITH, a citizen of the United States, residing at Brooklyn, in the county of Kings and State 5 of New York, have invented certain new and useful Improvements in Candy Molds and Presses, of which the following is a specification, reference being had to the accompanying drawings.

10 This invention relates to candy molds and presses, and particularly to a mold for forming lollipops, and has for its object to provide a device of this character capable of molding candy into various sizes and thicknesses.

15 Another object is to provide a device of this character including molds having adjustable bottoms.

A still further object of the invention is 20 to provide a device of this character which is simple in construction, compact in its form, and manually operable.

25 These objects are attained by the mechanism illustrated in the accompanying drawings, in which:—

Figure 1 is a side elevation and sectional view of the candy press and mold constructed in accordance with my invention;

Fig. 2 is a top plan view of the base and 30 mold;

Fig. 3 is a plan view of the handle detached from the base;

Fig. 4 is a transverse sectional view 35 through the base and one of the molds, showing the movable bottom;

Fig. 5 is a detail view of one of the movable bottoms;

Referring to the drawings, 5 indicates the base of the press having a pair of openings 6 and 7, the opening 7 being larger 40 than the opening 6. The end 8 of the press 5 extends above the surface thereof to provide a suitable connection for a handle 9 which is hinged thereto, as at 10. The broad end 11 of the handle 9 is beveled, as at 12, and projects over the upper surface of the end 8 and is intended to engage the same to limit the upward movement of the handle 9.

50 Secured to the upper surface of the base 5 is a plate 13 including a pair of molds 14 and 15, the mold 14 being larger than the mold 15. Each mold is provided with a slot 16 adapted to receive the skewer of the lollipop, while projecting from the opposite side of the mold is a lug 17 which is

internally threaded and intended to receive an adjusting screw 18 which extends into the opening of the mold. Slidably disposed in each mold is a movable bottom 19 comprising a top 20, a bottom 21, and sides 22. Formed in the side 22 is a groove 23, the rear wall 24 of which is inclined toward the bottom 21, the upper end of the wall 23 terminating flush and merging with the top 20 and the side 22. The adjusting screw 18 is intended to be disposed in the groove 23 and to engage the rear wall 24 to hold the movable bottom in the desired position. In order to hold the handle 9 in its extended position to permit unobstructed entrance to the mold, a spring 25 is provided and is secured to the base member 5, its side portions 26 being coiled and its intermediate portion 27 freely engaged with the lower surface of the handle 9. A hook 28 is pivoted to the base member 5, as at 29, and is intended to engage the free end of the handle 9 to hold the handle in engagement with the tops of the molds against the tension of the spring 25.

In operation, the bottoms 19 of the molds 14 and 15 are adjusted by rotating the screw 18, which causes the bottom to move either upward toward the top of the mold or 85 downward through the registering openings 6 and 7 in the base 5. The bottoms 6 and 7 are of sufficient thickness to withstand any pressure applied to the candy deposited in the mold by the handle 9. If desired, the 90 frame 5 can be made in various lengths and constructed to include any number of molds, each provided with a movable bottom so as to adjust the mold to the size of the lollipop desired.

95 From the foregoing, it will be readily seen that this invention provides a novel candy press and mold which is simple in construction, compact in form, is readily adjusted by means of a screw driver or like implement, and can be readily operated by hand, its simplicity permitting it to operate indefinitely without the necessity of repairs.

I claim:—

1. A device of the character described comprising a base, a movable press handle carried by said base, a plurality of molds on said base the tops of said molds being closed by the handle, each mold having a recess for the reception of a skewer, a movable bottom for 110 said mold, said bottom being movable to increase the size of the mold and length of the

recesses therein, and means for raising and lowering the bottom of the mold.

2. A device of the character described comprising a base, a movable handle carried by the base, a plurality of molds on said base between the handle and the base, each of said molds having a recessed wall for the reception of a skewer, a movable bottom for said mold movable through the mold and a registering opening in the base, and means carried by each mold and operatively engaged with the bottom to adjust, support and prevent rotation of said bottom.

3. In a device of the character described comprising a base, a movable handle carried by said base, a plurality of molds on said base between the base and the handle, each mold having a slot in one side thereof and a movable bottom having a peripheral, inclined recess, adjustable means carried by the mold and operatively disposed in the inclined recess for raising and lowering said movable bottom, said handle coöperating with the molds to form a substance deposited therein.

4. A device of the character described comprising an elongated base member, an extension on one end thereof, said base member having a series of graduated openings,

a press handle pivoted to the extension, a series of graduated molds carried by said base and terminating in the plane of the extension, said molds registering with the openings in the base, each mold having a bottom movable therethrough and the base, and a screw threaded in the side wall of each mold and arranged to engage the movable bottom to adjust and secure the bottom in the mold.

5. A device of the character described comprising an elongated base member, an extension on one end thereof, said base member having a series of graduated openings, a press handle pivoted to the extension, a series of graduated molds carried by said base and terminating in the plane of the extension, said molds registering with the openings in the base, each mold having a bottom movable therethrough and the base, and a screw threaded in the side wall of each mold and arranged to engage the movable bottom to adjust and secure the bottom in the mold, said handle serving as a top and operating means simultaneously for each mold of the series.

In testimony whereof I hereunto affix my signature.

BERRIEN H. SMITH.
